UNITED STATES PATENT OFFICE.

ISAAC LEVY, OF CLEVELAND, OHIO.

DESIGN FOR A FAUCET-BODY.

SPECIFICATION forming part of Design No. 31,467, dated August 29, 1899.

Application filed February 13, 1899. Serial No. 705,442. Term of patent 7 years.

To all whom it may concern:

Be it known that I, ISAAC LEVY, a citizen of the United States, residing at Cleveland, in the county of Cuyahoga and State of Ohio, 5 have invented and produced a new and original Design for Faucets, of which the following is a specification, reference being had to the accompanying drawings, forming a part thereof.

10 In the drawings, Figure I is a side elevation of a faucet having my design. Fig. II is forward end elevation of the same.

The essential or characteristic feature of my design consists in the configuration of the 15 upper portion of the upwardly-projecting part *c* of the faucet. The said part *c* is ar-

ranged upon the body of the faucet next rearward of the spout *a*. The upper portion of the part *c* comprises two annular convex ribs arranged the one *c'* above and diametrically 20 smaller than the other *c''*, and the stem *e* projects upwardly from and centrally of the upper rib *c'*.

What I claim is—

The design for a faucet-body, substantially 25 as shown and described.

Signed by me at Cleveland, Ohio, this 7th day of February, 1899.

ISAAC LEVY.
